[57] CLAIM

The ornamental design for a shoe midsole periphery, as shown and described.

DESCRIPTION

FIG. 1 is a side elevational view of one side of a shoe midsole periphery showing my new design;

FIG. 2 is a side elevational view of the other side of the shoe midsole periphery shown in FIG. 1;

FIG. 3 is a front elevational view of the shoe midsole periphery shown in FIG. 1;

FIG. 4 is a rear elevational view of the shoe midsole periphery shown in FIG. 1;

FIG. 5 is a cross-section generally along line 5—5 in FIG. 1;

FIG. 6 is a cross-section generally along line 6—6 in FIG. 2;

FIG. 7 is a cross-section generally along line 7—7 in FIG. 2; and,

FIG. 8 is a cross-section generally along line 8—8 in FIG. 1.

The broken line showing of a shoe upper and outsole in FIGS. 1-4 and 8 is for illustrative purposes only and forms no part of the claimed design.

FIG. 5

FIG. 1

FIG. 2

FIG. 7

FIG. 6

FIG. 4

FIG. 3
